UNITED STATES PATENT OFFICE.

ISAAC E. PALMER, OF MIDDLETOWN, CONNECTICUT, ASSIGNOR TO THE I. E. PALMER CO., OF MIDDLETOWN, CONNECTICUT, A CORPORATION OF CONNECTICUT.

COUCH-HAMMOCK.

1,094,921.

Specification of Letters Patent. Patented Apr. 28, 1914.

Application filed September 12, 1910. Serial No. 531,623.

To all whom it may concern:

Be it known that I, ISAAC E. PALMER, a citizen of the United States, residing at Middletown, in the county of Middlesex and State of Connecticut, have invented an Improvement in Couch-Hammocks, of which the following description, in connection with the accompanying drawings, is a specification, like letters on the drawings representing like parts.

This invention relates to couch hammocks. In order that the principle thereof may be readily understood, I have disclosed certain embodiments thereof in the accompanying drawings, wherein—

Figure 1 is an end elevation of a couch hammock embodying one form of my invention; Fig. 2 is a detail in end elevation showing a different position of the clamping bars; Fig. 3 is a view similar to Fig. 1 of a slightly modified form of the invention; Fig. 4 is an end view of the construction shown in Fig. 3; Fig. 5 is a detail in end elevation showing a slightly modified form of the invention; Fig. 6 is a detail in side elevation representing one of the suspension ends folded down onto the mattress; Fig. 7 is a detail showing a slightly modified form of the resilient wire loops. Fig. 8 is an end elevation of a hammock showing a slightly modified form of end suspension means. Fig. 9 is a detail in side elevation and vertical section indicating one manner of connecting the wire suspension end to a non-metallic end frame member; Fig. 10 is an underneath plan view of the construction shown in Fig. 9; Fig. 11 is a perspective view of a portion of a couch hammock frame composed of side members formed as angle irons and wooden end members. Fig. 12 is a plan view of a couch hammock frame embodying my invention; Fig. 13 is a side elevation thereof; Fig. 14 is an enlarged detail in side elevation and vertical section of the hammock shown in Fig. 13; Fig. 15 is a view similar to Fig. 14 of a slightly different form of hammock.

Couch hammocks are customarily provided with upright cloth suspension ends, although it has been proposed to use in conjunction with such cloth ends a series of links connected to the corners of the hammock frame and extending to the suspension rings. In accordance with my invention, I provide the hammock frame with a series of

continuous wire strands extending from substantially the corners of the frame and also from intermediate points and preferably so formed as to be longitudinally expansible, whereby the frame is not only yieldingly supported, but the use of wire strands of smaller diameter is permitted.

Referring first to the form of the invention shown in Fig. 1, an end member of the hammock frame is shown at 1. While any suitable type of frame may be provided, I preferably employ angle irons more particularly described hereinafter. The upstanding edge of each end member of the frame is provided with holes 2 adjacent the ends thereof and intermediate slots 3 for the reception of sufficiently elongated eyes 4 upon the lower ends of continuous wire strands 5, preferably terminating at their upper ends in eyes 6. The upper ends of said wire strands 5 are suitably connected to the suspension rings 7. Preferably for this purpose I provide a series of looped wires 8 which may be of a general inverted U or V shape. As herein shown, each looped wire is provided at its end with eyes 9 engaging the eyes 6 of the upright wires 5. The upright wires 5 are suitably held in relative position and preferably through the instrumentality of the looped wires 8 and transverse clamps 10, each composed of a pair of wooden or metallic bars as shown in edge view in Fig. 13, and secured flatwise by means of bolts or pins 11 at suitable points.

Inasmuch as the wires 5 are continuous and not composed of short connected links, there is no danger of the members of the suspension ends becoming entangled or displaced. The slots 3 are preferably provided in order that the intermediate strands 5 may accommodate themselves to the end strands 5 which preferably bear the strain of hammock suspension. Were not the slots 3 provided for some, at least, of the upright wires, there would be danger of buckling on the part of one or more of such upright strands.

It is important that the various suspension strands or stringing means of the suspension ends be each of the proper length in order to support the hammock frame in a horizontal position. It has heretofore been proposed to provide upright series of short suspension links extending to the suspension

rings, but such construction is objectionable inasmuch as it is difficult to provide links of the proper relative lengths to support the frame as desired. In other words, it is highly desirable, in order to support the frame in an exact predetermined position, to provide cords or ropes directly connected to the suspension rings 7. The employment of cords or ropes permits the adjustment of the suspension ends to a very fine degree of accuracy. In Fig. 1 I have represented such cords at 12, said cords extending from the rings 7 to the looped portions of the wires 8 as clearly shown in Fig. 1. The provision of one or more upright wires 5 between the edge suspension wires 5 provides a substantial support against which a pillow or the like may be positioned, such wire support not sagging or yielding as readily as the usual cloth suspension end. If desired, the clamping bars 10 may directly engage the wire loops 8 and are so shown in Fig. 2 wherein they are positioned above the upper ends of the upright wires 5. It is important that the hammock be resiliently supported and to that end I preferably provide the suspension wires with coils yielding sufficiently under strain of hammock suspension to afford a resilient support. In Fig. 3 I have represented suspension wires 13 provided at a suitable number of points with coils 14. These coils not only serve the purpose stated, but provide means for supporting transverse wires or other strands 15 which I may employ if desired to afford an even firmer end support. The transverse strands may be of wire, cord or any other suitable material. As shown, they are passed through the coils 14 and thus confined in position.

Couch hammocks of the general type herein shown, are generally provided with mattresses such as indicated at 16 in Fig. 6, these mattresses extending to varying distances above the upper face of the hammock frame. In order to permit the hammock suspension end to be folded flatwise upon the mattress when the hammock is not in use while still preserving the described continuous nature of the suspension wires, I provide, as shown in Fig. 5, brackets or rigid extensions 17 suitably secured to the corners of the hammock frame and extending upwardly to substantially the upper face of the mattress. To the said extensions the edge suspension wires 5 are suitably joined, preferably by forming the said wires 5 with eyes engaging the holes in said brackets or extensions. The intermediate wires 5 may terminate at substantially the upper face of the mattress in eyes 18 which are connected by short links 19 with the end members 1 of the frame so as to permit the suspension ends to be folded down as shown in Fig. 6. The continuous nature of the

edge suspension wires 5 prevents the entangling of the suspension end members as previously stated. It is evident that the coils 14 may be each formed of a plurality of turns or bends of the wires as indicated at 20, 20 in Fig. 7.

In Fig. 8 I have indicated a slightly modified form of my invention wherein the upper ends of the suspension wires 5 are provided with eyes to engage holes in a transverse spreader 21 at each end of the hammock. Each of said spreaders 21 is suitably connected to its suspension ring 7 in a suitable manner and herein by a plurality of continuous wires 22 each having coils 23 similar to those heretofore described. These coils enhance the resiliency of the hammock support. In this form of the invention, only the edge suspension wires 5 are represented as provided with coils 14 which receive the ends of the transverse wires 15 here represented as interwoven with the intermediate upright wires 5. The hammock frame may be of any suitable nature but in this form of the invention I have represented it as composed of angle iron side members 24 to which are suitably secured wooden end members 25. The frame may itself be provided with any suitable seating such, for example, as that indicated at 26 in Fig. 11. In order to connect the suspension wires 5 to the wooden cross bars 25, I have herein provided short wires 27 having at their outer, upwardly bent ends eyes 28 to receive the eyes at the lower ends of the wires 5, and at their inner ends eyes 29. Screws or bolts 30 and plates or washers 31 may be employed to secure said wires 27 to the under faces of the end members 25 of the frame.

In Fig. 12 I have illustrated a form of frame peculiarly adapted to receive the suspension ends heretofore described. Said frame is composed of side angle irons 38 and end angle irons 39 suitably connected at their meeting ends by bolts or otherwise. A frame thus constructed is substantial rigid in use and hence does not sag or stretch and the upper faces of the side and end members may readily be positioned in the same plane. The seating 40, and particularly if the same be provided with side and end springs, may be readily and simply connected to the end and side members by perforating the horizontal portions thereof to receive the ends of said springs as illustrated at 41. The upstanding edges of the end members may also be perforated as indicated at 42 in Fig. 13 to receive the eyes upon the lower ends of the wires 5. In this manner I am enabled to dispense with special screws or eyelets for connecting the suspension ends to the angle irons and for connecting the seating or springs thereof to said angle irons. I may, if desired, provide

cloth ends such as indicated at 43 in Figs. 13 and 14. Said cloth ends, if employed, are preferably connected to the clamping bars 10, the lower ends of said cloths preferably terminating below the mattress as indicated at 44. The said lower ends may be free, as they are indicated, or be connected to some suitable part of the frame. In Fig. 15 I have indicated the omission of said cloth ends.

It is of importance that the outer or edge suspension wires 5 be continuous, but, if desired, the intermediate suspension wires may be each formed of a series of links suitably connected together and, if desired, transversely connected by similar links. Preferably each continuous wire is provided with the described coils for the purposes stated, although in certain cases only 20 the edge or outer suspension wires need be so formed.

It will be apparent from the foregoing description that the wire suspension ends resiliently support the hammock frame and 25 that the continuous character of certain or all of the suspension wires prevents all danger of said wires becoming displaced or entangled. The employment of cords or ropes in conjunction with the suspension wires permits the use in each case of exactly the proper length of material to support the frame in correct position, and by the described construction all danger of buckling of the end and intermediate suspension wires is prevented.

The coils or turns of the suspension wires are readily expansible and contractible under strain and render said wires longitudinally expansible and therefore yieldingly support 40 the couch hammock frame. They are of sufficient diameter to contract under strain for the purpose described, even though transverse wires be threaded therethrough. It will be noted that the intermediate up- 45 right wires may or may not aid in supporting the hammock frame. If they do not co-act with the outer wires in supporting the frame, they serve to support the pillow or occupant or the cloth end of the hammock if the latter be employed.

Having thus described one illustrative embodiment of my invention, I desire it to be understood that although specific terms are employed, they are used in a generic and 55 descriptive sense and not for purposes of limitation, the scope of the invention being set forth in the following claims.

Claims:

1. A couch hammock comprising in combination a body receiving frame and suspension ends therefor, each of said ends consisting of a plurality of continuous wires connected at their lower ends to said frame and each extending upwardly substantially 60 straight throughout nearly its entire length

but provided with one or more expansible and contractible coils, thereby providing a slightly resilient hammock support.

2. A couch hammock comprising in combination, a body receiving frame and suspension ends connected thereto, each end consisting of lower and upper portions, each lower portion having continuous upright wires and each upper portion having cords connecting the lower portion to the suspension ring, whereby the length of the connection between the lower portion and the respective suspension ring may be accurately adjusted, the lower ends of each of said wires terminating at or adjacent to the 75 frame.

3. A couch hammock comprising in combination, a body-receiving frame and suspension ends connected thereto, said ends consisting of upright wires bent at intervals 85 into yielding coils, thereby providing a resilient hammock support.

4. A couch hammock comprising in combination, a body-receiving frame and suspension ends connected thereto, said ends 90 consisting of upright continuous wires having expansible and contractible coils.

5. A couch hammock comprising in combination, a body-receiving frame and suspension ends connected thereto, said ends 95 consisting of upright wires having coils constituting eyes and transverse strands positioned in said eyes.

6. A couch hammock comprising in combination a body receiving frame and sus- 100 pension ends connected thereto, said ends consisting of upright wires, and transverse clamps connecting said wires above the frame.

7. A couch hammock comprising in combination, a body-receiving frame and sus- 105 pension ends connected thereto, said ends consisting of upright, continuous wires, wire loops connected to the upper end thereof; and suspension cords extending from said 110 loops.

8. A couch hammock comprising a frame composed of side and end angle irons positioned in upright L-shape and rigidly connected together at their meeting ends, a seat- 115 ing connected to the inner edges of said angle irons, and suspension ends for the hammock, each end consisting of upright continuous edge wires and one or more intermediate upright continuous wires, said 120 wires passing through perforations in the upstanding edges of said angle irons.

9. A couch hammock comprising in combination, a body-receiving frame, upright wire suspension ends connected thereto, 125 clamps transversely connected to said wires adjacent their upper ends and cloth ends connected to and depending from said clamps.

10. A couch hammock comprising in com- 130

bination a substantially rectangular body receiving frame consisting of side and end members, said end members having one or more vertically elongated wire receiving slots, and suspension ends for said frame, each of said suspension ends consisting of a pair of upright wires connected to said end members, and one or more additional upright wires having the lower end or ends thereof secured in said slots to permit compensating adjustment of the said wires.

11. A couch hammock comprising in combination a substantially rectangular body receiving frame consisting of side and end members, said end members having one or more vertically elongated wire receiving slots, and suspension ends for said frame, each of said suspension ends consisting of a pair of upright wires connected to said end members, and one or more additional upright wires having the lower end or ends thereof secured in said slots, thereby to permit compensating adjustment of said wires,

said upright wires having relatively small, spaced, expansible and contractible coils, thereby providing a slightly resilient hammock support.

12. A couch hammock comprising in combination, a body receiving frame and suspension ends connected thereto, each of said ends consisting of a plurality of continuous wires connected at their lower ends to said frame and which extend upwardly substantially straight throughout nearly its entire length but provided with one or more expansible or contractible coils, thereby providing a slightly resilient hammock support together with transverse clamps connecting said wires.

In testimony whereof, I have signed my name to this specification, in the presence of two subscribing witnesses.
